JAMES H. NICHOLSON AND WILLIAM D. CAVIN, OF MADISON, GEORGIA.

FEMUR SPLINT.

Application filed May 31, 1927. Serial No. 195,470.

Our invention relates to a femur splint to properly locate and hold in place the upper and lower fragments of a fractured femur. It is well known in this art that when the femur is fractured, it has a tendency to contract and thus displace one fragment relative to the other, and it is one object of our invention to properly locate the fracture by stretching the leg until the fragments are properly located and then holding them in their properly located position.

Another object of the invention is to produce a splint that will fit different sized legs; that will be sanitary in all its parts and particularly in the parts that are pushed through the skin and soft tissues into the bone.

With these and other objects in view which will appear as the description proceeds we will now describe our invention in connection with the attached drawings in which:

Figure 1 is a top plan view of our device attached to a fractured femur, the soft tissues of the leg being omitted.

Fig. 2 is a side elevation of our splint; and,

Fig. 3 is a sectional view taken through the splint and the leg to which it is attached.

Referring to the details of the drawing 1 and 2 represent the upper and lower fragments respectively of a femur fractured at 3. In order to lengthen the femur, we provide side bars 4 and 5, the bar 4 having integral cradle arms 6 and 7 reduced at their ends and the bar 5 likewise have the integral cradle arms 8 and 9 with similarly reduced ends which overlap and a slot 10 is provided in each of said cradle arms through which extend set screws. The object of these extensible cradle arms is that the cradle made by the side bars and arms may be extended to fit any size leg by loosening the set screws 11 and 12, adjusting the cradle arms to fit the leg and then tightening up the set screws.

A similar splint composed of side arms 4', 5' and similar integral cradle arms 6', 7', 8' and 9'. The bars 4-4' and 5-5' are hinged to each other by hinges 14.

The bars 4, 5, 4', 5' have screw threaded openings 16-16' through which extend screws 17-17, 18-18, 17'-17', 18', 18', and the ends of the bars 4-4' and 5-5' have lugs 19-19 with a hole extending through the lugs and cotter pins 20-20' extending

through said holes to maintain the side bars 55 in straight lines.

To apply the splint to a femur, the side bars 4 and 5 and the cradle arms 6, 7, 8 and 9 are fitted over the leg and adjusted to fit the leg and the set screws on the extreme 60 right cradle arm are tightened to hold the splint in position at one end. The right hand steel pins 17-18 are inserted through the fleshy tissues of the leg and into the bone. If then the leg has been shortened, 65 the amount of shortening is ascertained by measuring the other leg of the patient to find out how much the fractured leg is to be lengthened. Having ascertained this, the hinged side bars are bent on the hinges 14 70 a sufficient amount so that when they are straightened, they will lengthen the fractured portions of the femur. This is accomplished by then fitting the left hand part of the splint over the leg and screwing in the 75 extreme left hand pins 17'-18' through the fleshy tissue and into the femur and then pressure put upon the hinged arms at the hinged portion to cause the side bars to straighten to the position shown in Fig. 2 80 and if desirable, additional screw pins may be forced through the fleshy tissue into the femur on either side of the fracture.

If there is danger of injury to the arteries of the thigh by thrusting the pin through 85 the tissues, especially on the inner side of the leg, the tissues may be opened to the bone and the pins passed through the opening.

This method of reduction and splinting 90 works directly with the bone, and the muscles and soft tissues are not relied on to assist in maintaining complete reduction and holding in true apposition the two fragments of the femur. By the use of the pins penetrating 95 the bone and the hinged splints, enough leverage can be had to reduce any ordinary fracture of the femur. When the splint is properly applied, there can be no shortening 100 of the limb and the splints may be taken apart for sterilization, and by their adjustable features they can be made to fit any sized leg and, furthermore, to fit different portions of the same leg.

What we claim as new is:

1. A femur splint comprising side bars connected by cradle arms, the side bars on opposite sides of the femur being hinged at

their meeting ends, and means passing through the side bars and adapted to penetrate the femur.

2. A femur splint comprising hinged sections, each section comprising side bars and cradle arms, the cradle arms being adjustable to fit legs of different size, pins passing through the side arms and adapted to penetrate the femur and hold the fragments of the femur in adjusted position.

3. A splint comprising hinged sections, each section comprising side bars and connecting cradle arms, pins passing through the side bars and adapted to penetrate the

femur, and means between the hinged sections to hold the side bars in alinement after the splint has been applied to the femur.

4. A splint comprising two sections hinged together at their meeting ends, each section comprising side bars and semi-circular cradle arms, said side bars having holes therethrough and pins adapted to be passed through said holes and to penetrate opposite fragments of a femur.

In testimony whereof we affix our signatures.

JAMES H. NICHOLSON.
WILLIAM D. CAVIN.
